F. C. GRIDLEY, OF HUDSON, WISCONSIN.

Letters Patent No. 73,799, dated January 28, 1868.

IMPROVED BED-BOTTOM.

The Schedule referred to in these Letters Patent and making part of the same.

TO ALL WHOM IT MAY CONCERN:

Be it known that I, F. C. GRIDLEY, of Hudson, in the county of St. Croix, and State of Wisconsin, have invented a new and improved Spring-Bed Bottom; and I do hereby declare that the following is a full, clear, and exact description thereof, reference being had to the accompanying drawings, making part of this specification, in which—

Figure 1 is a top view of the improved bed-bottom applied to a bedstead.

Figure 2 is a longitudinal section through fig. 1, taken in the vertical plane indicated by line x.

Figure 3 is an end view of the spring-bottom detached from the bedstead.

Similar letters of reference indicate corresponding parts in the three figures.

This invention relates to an improvement on that class of spring-bed bottoms which have their slats suspended from rails by means of elastic-rubber loops or bands, which allow the slats to have a free elastic motion independently of their own elasticity or flexibility.

The nature of my invention and improvement consists in attaching the slats, at their ends, to short transverse bars, by means of pins projecting from the upper edges of said bars, so that any one or more of the slats can be removed at pleasure, and reversed or turned end for end, should they after long use sag in the centre; and in suspending said transverse slat-supports from removable transverse head and foot bars, by means of elastic bands, applied at the extremities of each slat-support, as will be hereinafter described. And in combination with the foregoing arrangement, the invention further consists in the employment, at intermediate points between the end-straps, by which the slat-supports are suspended, of elastic and adjustable straps for levelling or adjusting and keeping the bed in a horizontal position, and compensating for any sagging which might take place, as will be hereinafter described.

To enable others skilled in the art to understand my invention, I will describe its construction and operation.

The drawings represent my invention applied to a common form of bedstead, consisting of head and foot portions A B, united together in any suitable manner by means of longitudinal rails C C. I make this explanation so as to be understood that my invention is applicable to any of the well-known forms of bedsteads. The only change required to be made is the addition to the posts of the bedstead, inside thereof, of blocks a a, which serve as supports and lateral abutments for the bed-bottom. At the ends of the bedstead, and supported in horizontal positions, are two transverse bars, b b, which are made strong enough to sustain the load which it is required of them to bear. The upper edges of bars b b are rounded, and their lower edges may be flat, as shown in fig. 2. The longitudinal slats D are made so that they will have an elastic flexibility, and holes are made through their ends by which they are attached to pins e e, rising perpendicularly from the upper edges of bars G G G G. The ends of the slats being thus attached to the bars G, it will be seen that the slats can be removed and turned over should they sag after long use. There are two bars, G, at the head, and two at the foot of the bed-bottom, and they are of such length as to move freely between the end-pieces a a, which support the fixed bars b b. These bars G are all of an equal length, and their inner ends nearly abut at the middle of the length of the bars b b, thereby forming, in conjunction with the slats which are supported upon them, as stated, a sectional bed-bottom consisting of two longitudinal, independent sections, as shown clearly in fig. 3. Each one of said sections is suspended independently of the other by means of elastic loops d d, which are slipped under the ends of the short bars G, and over the transverse bars b b, as shown in fig. 3. These elastic straps d will allow each one of the short bars G to rise and descend without necessarily moving any other one of these bars. In practice I shall make the straps d at the head of the bed much stronger than those at the foot of the bed, so that the bed will be sustained, when one or more persons are lying upon it, in or nearly in a horizontal position with respect to its length.

In fig. 3 it will be seen that I have applied to one of the sections of the bed-bottom two intermediate loops or straps, g g; these are made of rubber, and provided with buckle-fastenings, so that the loops can be shortened or lengthened at pleasure. One, two, or more of these auxiliary straps g may be applied to the ends of the sections composing the bed-bottom, as circumstances require. The straps g not only afford auxiliary supports for the sections, but, being adjustable, they serve as a ready means for adjusting and levelling the slatted bottom, so that it will be sustained in a horizontal plane, whether there be a weight upon it or not.

In the use of bed-bottoms having their slats suspended by elastic loops, as hitherto arranged, great inconvenience is experienced when there is more weight upon one side of the bed than upon the other, by the bed inclining to that side which preponderates. By my invention I provide in one bed-bottom two independently-suspended sections, each one of which is composed of a number of slats, and each one occupies one-half the width of the bed; and while this is the case, I also provide for sustaining each section by stronger or weaker loops, as may be required.

I do not confine my invention to any definite number of slats and elastic suspending-loops for the sections, as these will vary, according to the width of the bed-bottom and the load which the sections are required to sustain. When there is no weight upon the slatted bottom, the elastic suspending-loops will hold the slats firmly in contact with the bottom of the long rods *b b*, so that the slats will not become displaced in "making up a bed," or in removing the bed-bottom from a bedstead. I mean by the use of the term "sectional bed-bottom," one which is composed of two longitudinal sections, each one of which is composed of a number of slats, attached to separate supporting-rods, arranged beneath, and suspended from stationary rods, which are supported at their ends by the bedstead, as set forth.

Having described my invention, what I claim as new, and desire to secure by Letters Patent, is—

The arrangement of the bars *b* and *G*, elastic straps *g g*, and slats *D D*, in the construction of a bed-bottom, when such bottom is made in sections, and adjustable in the manner shown and described.

F. C. GRIDLEY.
